UNITED STATES PATENT OFFICE.

HARWELL L. BENNETT AND RUSSELL B. ADAMS, OF WESTERVILLE, OHIO.

STUMP-PULLER.

SPECIFICATION forming part of Letters Patent No. 515,317, dated February 27, 1894.

Application filed October 5, 1893. Serial No. 487,302. (No model.)

To all whom it may concern:

Be it known that we, HARWELL L. BENNETT and RUSSELL B. ADAMS, citizens of the United States, residing at Westerville, in the county of Franklin and State of Ohio, have invented a certain new and useful Improvement in Stump-Pullers, of which the following is a specification.

Our invention relates to the improvement of stump pullers and has particular relation to that class of stump pullers wherein a lifting screw is employed in conjunction with a derrick.

The objects of our invention are to provide an improved stump pulling machine of this class of such improved construction and arrangement of parts as to greatly facilitate the operation of removing stumps from the earth and to produce other improvements the details of which will be pointed out hereinafter. These objects we accomplish in the manner illustrated in the accompanying drawings, in which—

Figure 1 is a view in perspective of our improved machine shown in position for operation. Fig. 2 is a central vertical section of the derrick cap and operating nut. Fig. 3 is a detail view in elevation of the hitch clevis. Fig. 4 is a central sectional view of the permanent foot of one of the derrick posts. Fig. 5 is a transverse section through the lower portion of one of the derrick posts and its ground wheel and Fig. 6 is a view in perspective of one of the post supporting shoes.

Similar letters refer to similar parts throughout the several views.

a and *a'* represent the derrick beams or posts, the upper converging ends of which are surmounted and united by a cap piece *b*, the latter having formed therethrough a central opening *b'* which terminates on the under side of the cap in an enlarged and flaring mouth *b*². The opening *b'* communicates at its upper end with the central portion of an enlarged concavity or bowl shaped socket *b*³, which is formed in the upper portion of said cap *b*. Beneath the central flange of the cap piece *b* are formed at proper intervals suitable post sockets *c* for the reception of the upper ends of the derrick posts *a* and *a'*, which are secured therein.

Within the bowl shaped socket *b*³ is sup-

ported a bearing block *c'* which is substantially of a semi-circular form as shown, and the rounded portion of which is of such form as to fit and move within the socket *b*³. Through the center of this bearing piece *c'* is formed an opening *c*² and about the upper end of the opening *c*² is formed a circular groove *d*. Upon the upper side of the bearing piece *c'* is supported the correspondingly shaped base of a vertical operating nut *d'*, the under side of the latter having formed therein a circular groove *d*² which coincides with the groove *d* of said bearing piece. The circular conduit or boxing thus formed increasing, as shown in Fig. 2 of the drawings, the desired number of bearing balls *d*⁶, the latter serving as a frictional support for the nut *d'*. Through the central portion of the vertical nut *d'* is formed a screw threaded opening *d*³, and the flanged head of said nut is provided at opposite points with laterally projecting trunnions or studs *d*⁴.

As indicated in the drawings, the flaring lower end portions of the derrick beams or posts *a* are removably supported upon shoes *e*, each of the latter consisting of a ground block *e'* having a beveled outer end as indicated. Crossing this ground block *e'* at right angles therewith and secured thereto is an oblong block *e*², and upon this block *e*² is secured an upper plate or block *e*³ which is as shown, of greater length than said block *e*². This upper block or plate *e*³ is provided near the center of its length with a transverse shoulder *e*⁴, which forms substantially an obtuse angle *e*⁵, as indicated in Fig. 6 of the drawings. These shoulders *e*⁵ form a lateral bearing for the lower ends of the posts *a* which are seated upon the depressed portion of said block *e*³, within the angle formed by said shoulder.

Upon the inner side of each of the derrick posts *a* near the lower end thereof is adjustably mounted a suitable ground wheel *f*. As indicated in the drawings, each of these ground wheels *f* is journaled or mounted upon a suitable pin *f'* which projects outwardly in an inclined direction or at an angle slightly less than a right angle from a clip plate or bar *f*², the latter bearing against the inner face of the post *a* and being adjustably connected with a corresponding plate *f*³ across

the back of said post by means of connecting bolts f^4 , which pass on opposite sides of said post. Each of the wheels f is for reasons hereinafter given, normally supported in such 5 position as to cause its lower portion to project below the lower end of the post a . The post a' has its lower end embraced by the upwardly extending and inwardly inclined head lips g of a chair g' which has, as indicated in 10 Fig. 4, a central vertical pin g^3 on its under side, the latter being seated in a suitable socket g^3 formed in a ground shoe g^4 .

In their upper portions the derrick beams or posts a a' are connected, as shown in the 15 drawings, by transverse cross beams h , the notched ends of the latter being made to receive the inner angular corners of said posts. Each of these cross pieces h is provided with a central bolt h' which passes therethrough 20 and terminates on the under side thereof in an eye h^2 .

h^3 represents a clip the arms or yoke of which embrace opposite sides of each of the posts a and the outer projecting ends of which 25 are connected by a transverse clip plate h^4 one of which is drawn tightly against the outer side or face of each of said posts. From the inner corners of the clip h^3 beneath the ends of the cross pieces h extend horizontal brace rods i , the latter passing through the loops or eyes h^2 of the cross piece bolts h' . Depending from each of said eyes or loops h^2 beneath the brace rod i is a suitable 30 hanger or open link i^2 , with the inturned lower ends of which are engaged the upper and inner ends of brace rods i^3 , the latter extending outwardly and downwardly and connecting respectively with eye bolts k , which 35 pass through the posts a a' at points below the brace clips h^4 .

l represents a lifting screw the upper portion of which passes through and engages with the screw threaded opening d^3 of the nut d' from which said screw extends downward 45 passing loosely through a bearing block opening c^2 and cap openings $b' b^2$. The lower and unthreaded portion of the screw l passes through the upper end of a clevis frame m , the latter being supported thereon by means 50 of a collar or enlargement m' which is secured upon the lower end of said screw l and upon said clevis frame m . Through oppositely located openings formed in the two vertical and parallel arms of the clevis frame m is adapted 55 to pass loosely a supporting cross bar m^3 , the latter having one of its outer ends projecting upward as indicated at m^3 to form a substantially hook-shaped termination, and having its remaining or opposite end or the projecting 60 portion thereof beveled on its upper side toward its extremity. This beveled end portion m^4 is provided with a transverse opening which is adapted to receive a key pin m^5 .

As indicated in Figs. 1 and 3 of the drawings, the periphery of the screw collar m' has formed therein at desired intervals pin holes o in the desired one of which is adapted to be

inserted one end of a substantially L-shaped stop pin o' the latter projecting from said collar periphery at such distance as to result in 70 its contact with the vertical arms of the clevis m , when said screw is rotated.

As shown in Fig. 1 of the drawings, we provide the unthreaded portion of the screw l at 75 a point above the clevis m with a transverse handle rod p .

q represents the root chain which may be passed about the stump roots or engaged therewith in any desirable manner and the end links of which may, as shown in the drawings, 80 be made to engage respectively with the projecting end portion m^4 and the hook portion m^3 of the clevis bar m^2 . It is evident, however, that one or both of said end links may be engaged with said clevis bar between the 85 arms of said clevis, or that other well known means may be employed for connecting the chain and bar.

With the trunnions d^4 of the nut are connected, as indicated in the drawings, the upper separated end portions of a suitable sweep arm r , to the lower and outer end of which may be hitched a horse in the usual manner.

The method of operation of our improved stump puller is substantially as follows: The 95 root chain having been connected with the stump or its roots in any desirable manner and its ends connected with the clevis bar as hereinbefore described, the desired lifting movement is imparted to the screw by causing the horse hitched to the sweep to travel in a circular direction about the derrick. This movement of the sweep owing to its connection with the nut d' results in the rotation 100 of said nut and in the consequent feeding upward of the screw l which engages therewith. During this operation, it will be seen that any tendency of said screw toward rotation is obviated by the contact of the pin o' with the clevis arms. In case, however, it 105 is desired to slacken the chain q by hand, said screw l may be readily rotated in the desired direction by grasping the rod p and rotating the same with the hands, this being attempted only after removing the pin o' from 115 the head m' .

It is well known that in the class of stump pullers to which our invention relates, great strength is required of the derrick frame and the posts forming the same are necessarily of 120 such length as to make it exceedingly desirable that they be well braced and connected. By the method of bracing herein shown and described, which consist in the employment of the cross frame pieces h , clips h^3 , rods i 125 and i^3 , it will be observed that not only will a strong brace connection be afforded between said posts, but that with the exception of the bolt k the necessity of piercing the posts and thus weakening the same, is obviated.

By loosening the nuts which hold the clip bolts f^4 in position, it is evident that the position of the ground wheels f may be varied 130 as to height when desired, but these wheels

being so located on the posts *a* as to cause their lower portions to project below the ends of said posts, it is evident that said wheels will receive the burden of the weight when 5 the posts are moved off the ground blocks. It will be observed that these ground blocks or shoes are of such construction as to present various bearing surfaces and therefore decrease the possibility of their sinking too 10 far into the earth. In moving the derrick from said shoes, said posts are moved off the same in the direction opposite or away from the shoulders *e*⁵. Owing to the fact that the pins *f*' upon which the ground wheels *f* are 15 mounted, are inclined as hereinbefore described, it will be seen that said ground wheels will travel in forward and parallel directions when said derrick is moved.

The position of the stump to be pulled and 20 arrangement of its roots, may result in the attachment of the chain thereto being made in such manner as to throw the screw *l* out of a vertical position. In this case, it will be seen, that the bearing block *c*' will be allowed 25 to turn in its seat allowing the nut *d*' to adapt itself to the position of said screw.

Having now fully described my invention, what I claim, and desire to secure by Letters Patent, is—

30 1. In a stump pulling mechanism the com-

bination with a derrick frame, a lifting screw adjustably supported in said frame and a clevis *m* depending from said screw, and a cross bar detachably connecting said clevis arms, said cross bar having one of its ends 35 inclined or beveled and its remaining end turned upward or provided with a shoulder and a chain adapted to be detachably connected with said clevis cross bar, substantially as and for the purpose specified.

2. In a stump pulling mechanism the combination with the connected derrick posts, a cap therefor, a nut above said cap, a lifting screw passing through and engaging with said nut and means for rotating said nut, of a collar *m*' on the lower end of said screw and clevis *m* depending from said collar, a detachable cross bar in the lower end of said clevis adapted to support a chain, a hand rod connected with and intersecting said screw *l*, 45 there being peripheral pin holes in said collar *m*', and a pin *o*' adapted to be inserted therein, substantially as and for the purpose specified.

HARWELL L. BENNETT.
RUSSELL B. ADAMS.
